UNITED STATES PATENT OFFICE

LEMUEL D. CONROY, OF WHIPPLE, CALIFORNIA

DESIGN FOR A CIGARETTE DISPENSER

Application filed May 1, 1931. Serial No. 39,683. Term of patent 3½ years.

To all whom it may concern:

Be it known that I, LEMUEL D. CONROY, a citizen of the United States of America, residing at Whipple, in the county of Yavapai and State of California, have invented a new, original, and ornamental Design for Cigarette Dispensers, of which the following is a specification, reference being had to the accompanying drawings, forming a part thereof.

I claim:

The ornamental design for a cigarette dispenser substantially as shown.

LEMUEL D. CONROY.

CERTIFICATE OF CORRECTION.

Design Patent No. 84,777.

Granted August 4, 1931, to

LEMUEL D. CONROY.

It is hereby certified that the residence of the patentee in the above numbered patent was erroneously written and printed as "Whipple, California", whereas said residence should have been written and printed as Whipple, Arizona; and that the said Letters Patent should be read with this correction therein that the same may conform to the record of the case in the Patent Office.

Signed and sealed this 29th day of March, A. D. 1932.

M. J. Moore,
Acting Commissioner of Patents.
